UNITED STATES PATENT OFFICE.

CHARLES B. GOODSPEED, OF CHICAGO, ILLINOIS.

CAR-TRUCK.

941,515.

Specification of Letters Patent. Patented Nov. 30, 1909.

Application filed August 12, 1909. Serial No. 512,534.

To all whom it may concern:

Be it known that I, CHARLES B. GOODSPEED, of Chicago, in the county of Cook and State of Illinois, have invented certain new and useful Improvements in Car-Trucks; and I do hereby declare the following to be a full, clear, and exact description of the invention, such as will enable others skilled in the art to which it appertains to make and use the same.

This invention relates to improvements in car trucks and more particularly to a spring plank construction therefor, the object of the invention being to so construct a spring plank from a plate of metal that it shall possess adequate rigidity; be prevented from accidental displacement and so that it will serve the double purpose of a spring plank and also tying means for the side frames of the truck.

With this object in view the invention consists in certain novel features of construction and combinations of parts as hereinafter set forth and pointed out in the claims.

In the accompanying drawings, Figure 1 is a side elevation of a car truck showing the application of my improvements thereto. Fig. 2 is a view partly in plan and partly in horizontal section of the same. Fig. 3 is a view in perspective of the spring plank, and Fig. 4 is an edge view of the same.

1, 1, represent the side frames of a truck, each having a bolster opening 2 provided with parallel side-walls or columns 3.

The side frames of the truck are tied together by means of my improved spring plank 4. This spring plank comprises a sheet of metal having head portions 5 at its respective ends and between these head portions, the side edges of the sheet of metal composing the plank are slightly curved inwardly and bent to form strengthening ribs 6 which are disposed substantially at right angles to the face of the plank. The head portions 5 of the spring plank are provided in opposite edges with recesses 7 which, when said head portions are placed in the bolster openings of the side frames of the

truck, will receive the vertical side-walls or 50 columns 3 of said bolster opening. The spring plank will thus be properly held within the bolster openings; be prevented from displacement by the connection of its notched heads with the side-walls or columns of said bolster openings, and, on account of said connection of the spring plank with said side-walls or columns, the spring plank will serve to effectually tie the side frames together.

In Fig. 1 of the drawing a bolster 8 is shown entering the bolster opening of the side-frames 1 and springs 9 disposed between the bolster and the head portions of the spring plank.

Having fully described my invention what I claim as new and desire to secure by Letters Patent, is—

1. A spring plank for car trucks comprising a flat plate having depending integral ribs at its side edges between its ends and provided at the opposite sides of its ends with notches adapted to receive the truck columns.

2. A spring plank for a car truck, comprising a metal plate having head portions at its ends provided in diametrically opposite edges with notches, having its side edges between said head portions curved inwardly and provided with strengthening ribs.

3. The combination with the side frames of a car truck, said side frames having bolster openings with vertical side walls or columns, of a spring plank flat on top having notches in diametrically opposite edges of its end portions, said notches receiving the side walls or columns of the bolster openings in the side frames of the truck, and strengthening ribs at the respective edges of said spring plank between the 85 notched end portions thereof.

In testimony whereof, I have signed this specification in the presence of two subscribing witnesses.

CHARLES B. GOODSPEED.
